(57) CLAIM

The ornamental design for a jug, including ice tea jug and ice coffee jug, and part therefor, as shown and described.

DESCRIPTION

FIG. 1 is a perspective view of the jug, including ice tea jug and ice coffee jug, and part therefor showing my design thereof;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a cross-sectional view thereof taken along line 8—8 of FIG. 6.
